UNITED STATES PATENT OFFICE.

JAMES CARR, OF BRADFORD, ENGLAND.

LETTER-BOX.

SPECIFICATION forming part of Letters Patent No. 624,623, dated May 9, 1899.

Application filed November 30, 1897. Serial No. 660,225. (No model.)

To all whom it may concern:

Be it known that I, JAMES CARR, a subject of the Queen of England, residing at Bradford, England, have invented certain new and useful Improvements in Letter-Boxes, of which the following is a specification.

This invention relates to improvements in letter-boxes, particularly private letter-boxes; and its object is to prevent their contents from being tampered with or improperly dealt with.

In the accompanying drawings, Figure 1 represents a vertical section of my improved letter-box. Fig. 2 is a similar view of the upper portion of the box, showing some of the parts in the position they occupy when the letter-flap is opened to admit a letter. Fig. 3 is a sectional plan of Fig. 1 on the broken line *a b*. Fig. 4 is a back view of the box.

A represents the door or other part to which the box *B* is fixed. The letter-flap *C* is hinged in the ordinary way to the frame *D* around the aperture for admitting the letters. A lever *E*, pivoted to the lug *D*² on the frame *D*, is provided. One arm of this lever projects outside and terminates in a thumb or finger piece *E*², while a slot *E*³ in the other arm engages a stud *C*² on the letter-flap, and the portion *E*⁴ beyond said slot engages the top cross-piece *F* of the swing-partition *F*². The partition *F*² is approximately the full width of the box. It is hinged or pivoted to the brackets *G*, fixed to the sides of the letter-box, and extends from the back of the cross-piece *F* to the lower cross-piece *F*³.

When it is required to insert a letter, the thumb-piece *E*² is depressed, as shown in Fig. 2. This raises the other arm of the lever *E*, so that the slot *E*³ raises the letter-flap *C*, and the upper cross-piece *F* is pushed back, as shown, which brings the lower cross-piece *F*³ forward against the front of the box and separates the upper portion *B*², Fig. 2, of the box from the lower part *B*³. This effectually pre-

vents the contents of the lower portion of the box from being extracted through the aperture for admitting the letters. As an additional safeguard the inclined projection *H*, having a serrated edge *H*², is provided on the front of the box.

I claim—

1. In a letter-box, the combination with a box provided with an opening for the insertion of mail-matter, of a partition pivotally arranged within the box and adapted to swing to separate the lower portion of the box from the upper portion, a pivoted lever provided with a slot, one end of said lever projecting within the box and engaging the partition and the opposite end projecting beyond the box and adapted to be operated to effect the swinging movement of the partition, and a flap pivoted at one end and provided with a stud engaging within the slot, all arranged for co-operation as and for the purposes set forth.

2. In a letter-box, the combination with a box provided with an opening for the insertion of mail-matter, of a partition pivotally arranged within the box and adapted to swing to separate the lower portion of the box from the upper portion, a pivoted lever provided with a slot and adapted to engage at one end with said partition and to be operated at its opposite end to effect the swinging movement of the partition, a pivoted flap having a stud engaging within the slot, and a frame adapted for insertion within an opening in a door, and to which frame the said flap and lever are pivoted.

In testimony whereof I have hereunto set my hand in the presence of the two subscribing witnesses.

JAMES CARR.
